UNITED STATES PATENT OFFICE.

GEBHARD JAEGER, OF COLUMBUS, OHIO.

DRUM FOR CONCRETE-MIXERS.

1,322,575.

Specification of Letters Patent. Patented Nov. 25, 1919.

Application filed February 8, 1915. Serial No. 6,702.

To all whom it may concern:

Be it known that I, GEBHARD JAEGER, a citizen of the United States, residing at Columbus, in the county of Franklin and State 5 of Ohio, have invented a certain new and useful Improvement in Drums for Concrete-Mixers, of which the following is a specification.

The object of this invention is to provide 10 an improved mixing drum or vessel especially adapted for mixing the material to form concrete, it being my aim to provide a construction in which the mixing operation is performed thoroughly and more rapidly 15 than heretofore.

The invention is embodied in the construction and combination of features shown in the accompanying drawings and set forth in the following description and claims.

20 In said drawing—

Figure 1 is a view in elevation of the mixing device in which the invention is embodied, a portion of the drum being broken out to illustrate interior details.

25 Fig. 2 is a view in elevation looking at one side of the drum alone.

Fig. 3 is a similar view looking from a point ninety degrees from the point from which Fig. 2 is viewed.

30 Fig. 4 is a top plan view with the drum erect and in horizontal section on the line $\alpha-\alpha$ Fig. 3.

The body of the drum is constructed with a frusto-conical upper wall 5 on a base portion having opposite curved walls 6, 6, and opposite flat walls 7, 7, joined to said curved walls 6, 6, and a bottom portion 8 thereby forming four corners in the sides of the lower portion of the drum. The flat walls 35 7, 7, form, in effect, a peculiar interruption 40 of the continuity of a curved surface and if the drum be rotated while its axis is inclined to the vertical as seen in Fig. 1 the movement of the material is retarded by the flat 45 surfaces.

Coöperating with the peculiar structure of these walls near the bottom of the drum are blades 9, 9, which are offset a little from and are arranged inclined to the curved 50 surfaces 6, 6, and walls 7, 7, and extend in angular direction with reference to the axis of motion of the drum.

The drum is supported upon a yoke 10 having a spindle fixed on the yoke that enters a tubular bearing 11 rising from the middle of the bottom of the drum. This

yoke has trunnions at its ends that are journaled in standards 12 so that by swinging the yoke the drum can be oscillated as by handles at 13 on one of the trunnions to different positions for supplying material to the drum, mixing and discharging the same. The drum is also provided with a circumambient rack 14^a engaged by a pinion 14 on a shaft 15 for imparting rotary motion to the 65 drum. The construction with reference to the means for tilting the drum to different positions and imparting rotary motion to the drum in such tilted position are now well known in the art and need no further 70 detailing here.

In practice the drum is adjusted to have its axis stand at an inclination of about 35 degrees to the horizontal and is rotated in the direction indicated by the arrows in 75 Figs. 1 and 4. The materials to be mixed are supplied and made wet through the mouth of the drum at the smaller end of the frusto-conical portion. The result of the construction and operation is to cause the 80 materials to move inward and outward with reference to the mouth of the drum. On the flat surfaces the material slides toward the bottom of the drum while on the curved surfaces the material moves outward toward 85 the mouth of the drum and the combination also tends to impart a swirling motion to the fluent material. The material in its outward movement tends to accumulate against the blades and upon sufficient rotation it 90 falls off the blades onto the flat surfaces. The inward and outward movement generally of the material with reference to the mouth of the drum is therefore quite pronounced. The material in the drum therefore has in one sense two motions one the ordinary which is due to the rotary motion of the drum and the other due to the form of the walls, this latter movement being varied or supplemented by the presence of the 95 blades. The mixing effect is further aided by the projection of the tubular bearing into the drum. The material, when it slides off the blades, falls onto said tubular bearing and is divided and therefore more or less 100 mixed when uniting on the wall of the drum below the bearing.

The invention is susceptible of modification without departing from the gist of the invention as claimed.

110 What I claim is:

1. In a concrete mixer, the combination of

a mixing drum having a bottom and a feeding and discharging opening opposite the bottom, means for mounting the drum to rotate on an axis substantially at right angles to the bottom, said bottom having joined therewith curved and flat walls alternating with each other.

5. In a concrete mixer, the combination of a mixing drum having a closed bottom and a feeding and discharging opening opposite the bottom, means for mounting the drum to rotate on an axis substantially at right angles to the bottom, said bottom having joined therewith curved and flat walls alternating with each other and a blade secured to the wall of the drum diagonally transversely with reference to the curved wall.

10. In a concrete mixer, the combination of a mixing drum having a closed bottom and a feeding and discharging opening opposite

the bottom, means for mounting the drum to rotate on an axis substantially at right angles to the bottom, said bottom having joined therewith curved and flat walls alternating with each other, a blade on the side of the drum, and an axial projection from said bottom coöperating with said curved and flat walls and said blade.

15. In a concrete mixer, the combination of a mixing drum having a closed bottom and feeding and discharging opening opposite the bottom, means for mounting the drum to rotate on an axis substantially at right angles to the bottom, said bottom formed with a curved wall interrupted by a retarding wall forming a continuation of said curved wall, substantially as described.

20. GEBHARD JAEGER.
